UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed January 10, 1923. Serial No. 611,755.

To all whom it may concern:

Be it known that I, CHARLES DAVID BONSALL, a citizen of the United States, and a resident of the city of Pittsburgh, county of 5 Allegheny, and State of Pennsylvania, have invented a new and useful Improvement in Car Roofs, of which the following is a specification.

This invention relates to car roofs of the 10 all-steel riveted-up type wherein self-supporting roof sheets extend from side plate to side plate of the car and are formed along their side margins with lapping portions that are rigidly secured together to form 15 hollow weather-proofing seams or joints that function as car-lines.

One of the principal objects of the present invention is to increase the strength and 20 rigidity of the roof by improving the sectional shape and arrangement of the lapped portions of adjacent sheets. Another object is to utilize the seams or the joints as drain channels for draining off water that may enter said joints. Other objects are 25 to reduce the weight of the roof, to simplify the construction thereof and to cheapen the cost of manufacture.

The invention consists principally in shaping and arranging the cooperating 30 marginal portions of the roof sheets to form hollow weather-proofing seams or joints that are better fitted for taking care of contemplated stresses; and it also consists in the parts and in the arrangements and combinations of parts hereinafter described and 35 claimed.

In the accompanying drawing, wherein like symbols refer to like parts wherever they occur,

40 Fig. 1 is a plan view of a portion of a car roof comprising my invention;

Fig. 2 is an enlarged transverse section through one-half of the car roof on the line 2—2 in Fig. 1;

45 Fig. 3 is a cross-section through one of the seams at the ridge on the line 3—3 in Fig. 1;

Fig. 4 is a similar section taken midway of the ridge and eaves on the line 4—4 in 50 Fig. 1;

Fig. 5 is a similar section taken at the side plate on the line 5—5 in Fig. 1; and

Fig. 6 is a cross-section through the eaves

portion of the roof, the section to be taken through one of the seams on the line 6—6 in Fig. 1.

The roof shown in the accompanying drawing comprises metallic roof sheets 6 that extend transversely of the car from eaves to eaves thereof with their side 60 margins overlapping. The roof sheets slope upwardly from the eaves to the ridge and are supported at their eaves ends on metal side plates 7. The roof sheets are rigidly secured to the side plates 7 by rivets 8 and are provided with downturned eaves flanges 9 which overhang the outer edges of the side plates.

One side margin of each roof sheet is pressed up to form a strengthening rib or 70 seam flange A; and the other side of the margin is pressed up to form a strengthening rib or seam flange B, both ribs extending from end to end of the sheet. The roof sheets are assembled on the car by 75 placing the type A rib of one sheet over the type B rib of the next adjacent sheet to form upstanding hollow seams or joints that extend from side plate to side plate and serve as carlines.

The ribs of both types have a maximum depth at the ridge and gradually decrease in depth towards the eaves where they are curved downwardly and merge into the plane of the sheets at the eaves ends thereof. The rib or seam flange A of each roof sheet is preferably of substantially inverted L-shaped section; that is, said rib A has a nearly vertical web portion at the top of which is an outwardly projecting flange. 80 The rib or seam flange B at the other side of said roof sheet has an inverted L-shaped section at the ridge; and on opposite sides of the ridge the outwardly projecting lateral flange of said rib B has a channel 10 85 pressed therein which has a depth at the eaves corresponding to the depth of said rib and gradually decreases in depth towards the ridge where it merges into the plane of said lateral top flange. The lapped 90 ribs A and B of adjacent sheets are rigidly secured together by rows of rivets 11 which extend vertically through the lateral top flanges of said ribs on opposite sides of the channel 10 formed in the underlying lateral 100 flange of the rib B.

Running boards 12 are arranged lengthwise of the car at the ridge and are securely bolted to the lateral flanges of channel-shaped running board saddles 13. The running board saddles 13 rest on and are rigidly secured to the lapped ribs A and B of adjacent sheets by means of the rivets 11 that secure said ribs together.

The top of the downwardly curved eaves 10 end portion of each rib or seam flange A is provided with an opening 14. These openings permit the escape of water that may accumulate in the channel 10 formed in the rib or seam flanges B.

By the arrangement described, the lapped ribs A and B of adjacent sheets co-operate to form a seam construction whose cross-sectional shape changes from a relatively deep inverted channel at the ridge to a shallow inverted channel at the eaves whose middle portion is provided with a hollow box-girder.

It is noted that the seam or joint construction produced by the co-operating ribs of the type A and B accomplish the various functions of a carline. The sectional shape of the seams or joints at the ridge serves to take care of the vertical roof load, and the cross-sectional shape of the seams or joints at the eaves serves to take care of the stresses that tend to rack and twist the car body and distort it endwise. This increased strength in the seams or joints enables a roof to be produced that will be stiffer and stronger than previous roofs of the same weight of metal. It is also noted that this seam construction provides a trough for carrying off any water that may enter the joints of the seams.

The invention is not limited to the precise shapes and arrangements of parts shown and described.

What I claim is:

1. A car roof comprising a plurality of roof sheets whose adjacent marginal portions are offset upwardly and lapped and secured together to form weather proofing seams, the lapping portion of the lower sheet having a channel formed therein that extends longitudinally thereof.

2. A car roof comprising a plurality of roof sheets whose adjacent marginal portions are offset upwardly and lapped and secured together to form weather proofing seams, the lapped portion of the lower sheet of a seam having a channel formed therein that extends lengthwise thereof and increases in depth toward the eaves.

3. A car roof comprising a plurality of roof sheets whose adjacent marginal portions are offset upwardly and lapped and secured together to form weather proofing seams of varying depth, the extent of offsetting being greatest near the ridge and decreasing towards the eaves, and the lapping

portion of the lower sheet of a seam having a channel of varying depth formed therein that extends lengthwise thereof.

4. A car roof comprising a plurality of roof sheets whose adjacent marginal portions are formed into hollow seams whose cross-sectional shape changes from an inverted channel at one point to an inverted channel at another point having a hollow box girder formed therein.

5. A car roof comprising a plurality of roof sheets extending from eaves to eaves and having their adjacent side marginal portions formed into stiffening ribs that are lapped and positively secured together to form weather proofing seams, said ribs having a maximum depth at the ridge and gradually decreasing in depth towards the eaves where they merge into the plane of the sheets, the underlying rib of a seam having a channel formed therein which has a maximum depth adjacent to the eaves and gradually decreases in depth towards the ridge where it merges into the plane of the top of said rib.

6. A car roof comprising a plurality of roof sheets extending from eaves to eaves and having their adjacent side marginal portions offset upwardly and are lapped and positively secured together along two lines to form weather proofing seams, said seams having a maximum depth at the ridge and gradually decreasing in depth towards the eaves where they merge into the plane of the sheets, the underlying sheet of a seam having a channel formed therein between said lines which has a maximum depth adjacent to the eaves and gradually decreases in depth towards the ridge where it merges into the plane of the top of said rib, the eaves end portion of the overlapping sheet being provided with an opening.

7. A car roof comprising a plurality of roof sheets extending from eaves to eaves thereof and having their adjacent side marginal portions offset upwardly and lapped to form seams, said lapped portions being rigidly secured together along two lines extending lengthwise thereof, the portion of the underlying sheet between said lines being formed into a channel.

8. A car roof comprising a plurality of roof sheets extending from eaves to eaves thereof and having their adjacent side marginal portions offset upwardly and lapped to form seams, the extent of offsetting being greater at the ridge than at the eaves, said lapped portions being rigidly secured together along two lines extending lengthwise thereof, the portion of the underlying sheet between said lines being formed into a channel which has a maximum depth adjacent to the eaves and merges into the plane of the rib adjacent to the ridge.

9. As an article of manufacture a car

roof sheet, said sheet having its side marginal portions offset upwardly, the offset portion at one side margin of said sheet being formed with a channel that extends longitudinally thereof.

10. As an article of manufacture a car roof sheet, said sheet having its side marginal portions formed into hollow ribs, the rib at one side margin of said sheet being formed with a channel that extends longitudinally thereof and the rib at the other side margin of said sheet having an opening in each end.

11. As an article of manufacture a car roof sheet, said sheet having its side marginal portions offset upwardly, the extent of offsetting decreasing from the middle of the sheet towards each end, the offset portion at one side margin of said sheet being formed with a channel that extends longitudinally thereof.

12. As an article of manufacture a car roof sheet, said sheet having its side marginal portions formed into hollow ribs that decrease in depth from the middle of the sheet towards each end, the rib at one side margin of said sheet being formed with a

channel that extends longitudinally thereof and decreases in depth from the end portions of the sheet towards its middle 30 portion.

13. A car roof comprising a plurality of roof sheets whose adjacent side marginal portions are offset upwardly and lapped and rigidly secured together along two lines 35 to form weather proofing seams, the portion of the under sheet between such lines having a channel formed therein that extends from the ridge portion of the sheet to the eaves ends thereof. 40

14. A car roof comprising a plurality of roof sheets whose adjacent side marginal portions are offset upwardly and lapped and rigidly secured together along two lines to form weather proofing seams, the portion of the under sheet between such lines having a channel formed therein that extends from the ridge portion of the sheet to the eaves ends thereof and is of greater depth at the eaves than at the ridge. 45

Signed at New Kensington, Pennsylvania,
this 4th day of January, 1923.

CHARLES DAVID BONSALL.
